(57) **CLAIM**

The ornamental design for a floor tile connector, as shown and described.

DESCRIPTION

FIG. 1 is a bottom, perspective view of a floor tile connector; FIG. 2 is a bottom plan view of the floor tile connector of FIG. 1;

FIG. 3 is a top plan view of the floor tile connector of FIG. 1; and,

FIG. 4 is a side view of the floor tile connector of FIG. 1. The design is the portion of the floor tile connector shown in solid lines in the drawing. The portions shown in stippled lines do not form part of the design.

The applicant reserves the right to: 1) convert some or all of the broken lines to solid lines; or 2) convert selected solid lines to broken lines during the course of prosecution and/or in one or more continuation applications, since the figures convey that the inventors had possession of the solid line features and the stippled line features as of the filing date.
